UNITED STATES PATENT OFFICE.

STEPHEN JARVIS ADAMS, OF PITTSBURG, PENNSYLVANIA, ASSIGNOR TO
MARCELIN C. ADAMS, OF PITTSBURG, PENNSYLVANIA.

SAND-MOLDING APPARATUS.

SPECIFICATION forming part of Letters Patent No. 697,386, dated April 8, 1902.

Application filed March 30, 1897. Serial No. 629,919. (No model.)

To all whom it may concern:

Be it known that I, STEPHEN JARVIS ADAMS, a resident of Pittsburg, in the county of Allegheny and State of Pennsylvania, have invented a new and useful Improvement in Sand-Molding Apparatus; and I do hereby declare the following to be a full, clear, and exact description thereof.

My invention relates to apparatus for forming molds, and particularly to apparatus adapted to form molds by what is known as the "jarring process," where the sand is placed around the patterns which project upwardly within the flask, a surplus of sand being held in a reservoir above the flask and the whole mass is raised upon a table or support, which is permitted to drop or descend quickly and strike a stationary block, and so impart a jar to the sand within the flask, a sufficient number of these jars being imparted thereto to compact the sand. This way of forming molds has been very successful and largely used.

The present invention is devised to overcome certain difficulties with the apparatus heretofore employed for the purpose, the principal difficulties of which will be herein-after stated.

It was found that with the ordinary apparatus it was difficult to provide an absolutely vertical drop to the flask, and therefore that as the jar was not in an exact perpendicular direction and the jar was the means of packing the sand the sand in following the direction of the jar would pack in one side or end of the mold or against one side or face of the pattern more perfectly than against that opposite thereto.

One object of the present invention is to provide for an absolutely vertical drop, so as to get a perpendicular jar, and this is accomplished, first, by providing lifting mechanism connected with the jarring apparatus by a flexible connection and mounting the jar-ring apparatus in vertical guides a sufficient distance apart to insure absolutely vertical movement in jarring.

In the practice of the jarring process above described the reservoir, which rested upon the top of the flask, consisted of a shallow frame open at both ends, and it was found that the

jarring stroke caused a rebound in this shallow body of sand within the frame and in the upper part of the flask, and that though the sand would be packed evenly and solidly around the lower portions of the patterns it was liable, on account of this rebound, to be insufficiently packed in the upper part of the flask; and one object of the present invention is to provide for the even packing of the mold throughout by the employment of a long sand-feeding chute, which is of a sufficient length to provide a body of sand which will prevent rebound of sand within the flask, and therefore that the sand fed therefrom into the flask while affected by the jar cannot rebound, which insures the proper packing of the sand within the flask.

The regular custom has been to support the movable reservoir directly upon the flask, which has made it necessary to employ a shallow reservoir as a reservoir of sufficient length to provide a body of sand which will prevent rebound of sand within the flask would be too heavy for handling, and this difficulty I overcome by supporting the sand-feeding chute upon the jarring-table independent of the flask, providing for the insertion of the flask by a horizontal movement under this chute and providing means for cutting off between the chute and flask, so that after the formation of the mold it can be handled for the withdrawal of the patterns or of the steps in connection with the formation thereof.

My invention also consists in certain other improvements looking to these general ends, which will be herein-after described and claimed.

To enable others skilled in the art to make and use my invention, I will describe the same more fully, referring to the accompanying drawings, in which—

Figure 1 is a face view of the apparatus, partly broken away and showing the interior of the apparatus in section; and Fig. 2 is a side view, the side support of the main frame being withdrawn to show the operative mechanism, Fig. 1 showing the apparatus in its raised position, and Fig. 2 in its lowest position. Fig. 3 is a cross-section on the line 3-3, Fig. 1. Fig. 4 is a cross-section on the line 4-4, Fig. 1. Fig. 5 is a view of the cutter and

sleeker; and Fig. 6 is a perspective view of the flask and the base of the sand-feeding chute, illustrating the cutting and sleeking of the mold, said view being partly broken away.

Like letters of reference indicate like parts in each.

The construction of the apparatus is well shown in the drawings, which I will now describe, the general parts of it being the framework A, which rises from the bed or floor b', which also supports the jarring-block b, said framework being composed of upright standards a and any suitable cross-beams a' a².
 15 The apparatus has also the jarring-table c and the sand-feeding chute d, which is, at least during the jarring operation, supported on said table independently of the flask, being preferably permanently supported on the table. The
 20 upright standards a carry suitable guides or guideways which, as shown, are placed a sufficient distance apart to insure the absolutely vertical movement of the jarring-table and sand-feeding chute. As illustrated, there are
 25 the lower guideways e, which are engaged by guides e' on the jarring-table c, and the upper guideways f, engaged by guides f' near the upper end of the chute d. As it is desirable to protect the guides and guideways from
 30 contact with the sand, which is liable to cut and wear into the same, I prefer to extend the guides e' upwardly from the jarring-table c to a point above the base of the chute d, so that there will be no liability to the sand entering between the guides and guideways.
 35 The sand-feeding chute is supported some distance above the jarring-table on suitable legs d' d², the legs d' being placed two on each side near to the front and back faces of the
 40 chute, while the legs d² are placed about midway and provide bearings for the cams g, which act to clamp upon the jarring-table the flask h in which the mold is made, the flask h having lugs h' in line with said cams
 45 g, so that after the flask is inserted under the sand-feeding chute the cams may be thrown down by means of the handles g' and force the flask against the jarring-table and hold it firmly during the jarring operation. Suitable
 50 rests or supports for the handles g' when the cams are not in use may be provided upon the legs d². It will be noticed that between the flask h and chute d a slight space is left, as at h², this space being provided for the
 55 passage of the cutting and sleeking mechanism, referred to hereinafter.

The sand-feeding chute is made with a slight upward taper, increasing gradually in diameter from the top to the bottom, so as to prevent the sand from sticking therein. It is preferable to make this chute from eight to ten feet in height, so that it will hold a large body of sand and that the sand in the lower part thereof will be sufficiently packed in any ordinary diameter of chute to maintain the weight of the sand above without dropping

out. Its principal function is to resist any tendency to rebound of the sand within the flask, providing in this way a body of sand which can only be caused to move by the jars imparted to the chute and which will remain therein when the flask is withdrawn from under the chute and before it is again placed thereunder for the making of the next mold. If any difficulty is experienced in the holding of the sand in the chute, it can be overcome by the employment of a few wires d³, extending across the base thereof, as illustrated in Fig. 4; but this is only necessary in forming molds of considerable width. The supply of sand may be maintained within the sand-feeding chute in any suitable way, being fed thereto by proper mechanism. One suitable way is illustrated in Fig. 2, in which a suitable stationary reservoir i is provided at one side of and above the sand-feeding chute, and below the said reservoir i and above the chute d is a sand-transfer box i', which rests on the platform i² and slides from said platform over the sand-feeding chute so as to receive sand from the reservoir i and feed it thereto, the transfer-box carrying a plate i³, extending back from the upper edge thereof, so as to close the reservoir i when the sand is being fed into the chute d. The necessary movement can be imparted to the transfer-box i by a piston-rod i⁴, operated by suitable means or any other suitable mechanism.

In order to raise and lower the jarring-table and its sand-feeding chute, I may employ any suitable vertically-moving mechanism operating in any suitable way, the preferable way being by steam or air pressure, operating within an engine K, having a cylinder k, which operates through the piston k' a piston-rod k², from which the sand-feeding chute d is suspended by a flexible support l, which is preferably formed of a wire rope, the advantage of this construction being that the power to lift the table and chute being applied through a flexible connection permits the same to move as guided from the frame, and therefore permits it to move in an exactly vertical course in dropping, the lifting mechanism having no control whatever upon the dropping of the table and its chute. In order to give a direct upward pull of the wire rope l to the chute, it is passed first around a pulley k³ at the base of the piston-rod k² and thence passes around the pulleys l', supported on the cross-beam a' and in such position that the rope then passes in a true vertical course down to the loops l², by which it is connected on each side to the sand-feeding chute d. The admission and escape of air to the cylinder k of the lifting-engine is controlled by any suitable valve mechanism operating through the valve-chest m, the valve-rod m' being under any suitable control. The construction of the engine will of course require a rapid escape of the air to permit the jarring stroke; but this can be obtained by the use of

a cylinder somewhat longer than the stroke, which will at the same time permit the piston to cushion before reaching the lower end of the cylinder, while the stroke of the piston and its rod may be controlled by a suitable stop 5 *n*, the piston-rod extending up through the upper cross-beam *a*², to which the cylinder *k* is connected, and having a head or enlargement *n'*, which engages with said stop *n*, a suitable spring or other cushion *n*² being interposed between the same, as found necessary.

The stroke of the apparatus—that is, the lift of the table and its chute above the jarring-block *b*—of course depends upon the mold being made and the particular stroke for the packing of the sand. On an average a lift 15 of about one foot will be sufficient, and the cylinder and valve mechanism can of course be made of proper construction to give such stroke, permitting a free drop and the cushioning of the piston.

It will of course be understood that the sand is packed solidly in the lower part of 25 the feeding-chute and the upper part of the flask and that before the finished mold can be withdrawn this sand must be properly cut, so as to permit the withdrawal of the flask. As above stated, a space *h*² is left between 30 the top of the flask *h* and the bottom of the sand-feeding chute *d*, the space varying in different mechanisms, but being generally about one-half an inch in width. To cut off the sand, I employ a cutting and sleeking 35 frame *p*, which, as shown in the drawings, is formed of a light frame having two arms *p*', extending forward and carrying at the front end a wire *p*², stretched taut between said arms, the arms being of a thickness such as 40 to pass easily through the space *h*² between the flask and chute, so that when this frame is pushed horizontally through said space the thin wire-cutter will cut through the sand and so form a division thereof, separating the sand 45 within the flask from that within the chute. As the wire-cutter forms a rough surface upon the sand in order to sleek the sand within the flask and also to aid in packing the sand at the base of the feeding-chute, I employ 50 back of the sand-cutter the sand-sleeker *p*³, which, as shown, is formed of a slat corresponding in thickness to the frame *p* and tapering gradually to an edge on one or both sides, as at *p*⁴, so that as the wire cuts through 55 the sand this sleeker will follow it and smooth over the surface of the sand both above and below it, preferably having this action both in the entering and withdrawing stroke of the frame and so smoothing the surface of the 60 finished mold and packing the sand up into the chute *d*, which will increase the binding force of the sand at the base thereof, and so aid the same in holding the sand above it within the chute.

65 When the apparatus above described is employed in the making of molds, I generally proceed as follows: The sand for filling the

flask may either all be drawn from the sand-feeding chute or a certain portion of mealy sand, such as will conform more perfectly to 70 the patterns *r*, which extend up from the pattern-plate *r'* into the flask *h*, may first be filled around said patterns before the pattern-plate and flask are placed in position under the sand-feeding chute, such feeding of mealy sand 75 being accomplished by hand or in any suitable way. The pattern-plate, with the flask resting thereon, is placed on the jarring-table *c* under the sand-feeding chute and is clamped in place by the cams *g*. The apparatus is 80 then ready for the making of the mold and through the movement of the valve mechanism controls the lifting-engine *K*. The jarring-table and its sand-feeding chute are raised and dropped, so that the jarring-table *c* strikes the 85 jarring-block *b* and imparts the jar to the same, the action of which is to jar the sand from the sand-feeding chute down into the flask, either filling the flask entirely through 90 said chute when the empty flask, with its patterns, is placed under the same or filling the portion of the flask unfilled with sand. In so doing the sand from the chute acts as a weight upon the sand in the flask and prevents the rebound of the sand from the jar in the upper 95 part of the flask, which has been the serious defect in prior methods employed in this system of molding, so that the entire effect of the jar in packing the sand within the flask is obtained, the whole body of sand within the 100 long feeding-chute moving down at each jar and holding the sand to the position brought by the jar without permitting any rebound thereof, the only rebound being in the sand in the upper part of the sand-feeding chute, 105 where it can have no effect whatever upon the sand packed within the flask. Any suitable number of jars may thus be imparted to the sand within the flask and chute to give the necessary degree of solidity within the flask, 110 as can be easily determined according to the length of the stroke and the depth of the mold to be formed. When the mold is completed, the operator grasps the cutting and sleeking frame *p* and pushes it through the space *h*² 115 between the flask and chute, and the wire *p*² cuts through the sand, while the sleeker *p*³, following the wire, smooths the surface of the sand both of the mold and at the bottom of the chute, so finishing the top surface of the 120 mold and aiding in the packing of the sand at the base of the chute, which will increase the hold thereof and assist it in holding the mass of sand above it. The clamping-cams *g* are then withdrawn and the flask drawn out horizontally and the patterns withdrawn and any necessary cores inserted in the mold, thus 125 completing it. A new flask may then be placed upon the pattern-plate and the operation repeated. The sand within the feeding-chute 130 can be maintained at the proper height by means of any suitable feeding mechanism, such as that shown in Fig. 2, the operator moving the transfer-box *i*', which has received

sand from the stationary reservoir *i*, over the chute *d* at suitable intervals.

With the special apparatus above described and mounted in the way shown certain other advantages are obtained, such as the guiding of the movement of the jarring-table and its sand-feeding chute in practically perfect vertical lines. This is accomplished, first, because it is mounted in guides at a distance apart so that even if there was tendency to side movement it would be well resisted by such guiding means, and, further, on account of the flexible connection between the lifting means, such as the lifting-engine, above described, and the jarring-table or its chute. The advantage from this device is that even if there be a tendency to side movement in the lifting mechanism on account of the flexible connection used this tendency cannot be imparted to the actual jarring mechanism. Therefore such jarring as would cause a packing of the sand to one side or the other of the flask is prevented.

What I claim as my invention, and desire to secure by Letters Patent, is—

- 25 1. In sand-molding apparatus, the combination of a jarring-table, a flask, and a sand-feeding chute supported on the table independent of the flask, substantially as set forth.
- 30 2. In sand-molding apparatus, the combination of a jarring-table, a flask, and a sand-feeding chute permanently supported on the jarring-table independent of the flask, substantially as set forth.
- 35 3. In sand-molding apparatus, the combination of a jarring-table, a flask, a sand-feeding chute supported on the table independent of the flask, and clamping means between said flask and chute, substantially as set forth.
- 40 4. In sand-molding apparatus, the combination of a jarring-table, a flask, a sand-feeding chute supported on the table independent of the flask, and cams on the sand-feeding chute engaging with the flask, substantially as set forth.
- 45 5. In sand-molding apparatus, the combination of a jarring-table, a flask, a sand-feeding chute above the flask, stationary vertical guideways, guides on the chute engaging said stationary guideways, and mechanism for raising the table and chute, substantially as set forth.
- 55 6. In sand-molding apparatus, the combination of a jarring-table, a sand-feeding chute permanently secured above the same, guides engaging with said table and with the upper part of said chute, and lifting mechanism for raising the table and chute, substantially as set forth.
- 60 7. In sand-molding apparatus, the combination of a jarring-table, a sand-feeding chute permanently secured thereon, guides engaging with the table and with the upper end of the chute, lifting mechanism above the chute and a flexible connection between said lifting

mechanism and the chute, substantially as and for the purposes set forth.

8. In sand-molding apparatus, the combination of a jarring-table, a sand-feeding chute permanently secured thereon, a lifting-engine above and connected to the chute and having a piston-rod extending above the engine, a head on said piston-rod and a stop engaging the said head, substantially as set forth.

9. In sand-molding apparatus, the combination of a jarring-table, a sand-feeding chute permanently secured thereon, lifting mechanism above the chute having a vertical depending rod carrying a pulley, guided pulleys above the chute and a flexible connection passing from said chute over said guided pulleys and over the pulley on the depending rod, substantially as set forth.

10. In sand-molding apparatus, the combination of a jarring-table, a flask, a sand-feeding chute supported on the table a short distance above the top of the flask and cutting mechanism adapted to pass horizontally through the space between the chute and flask, substantially as and for the purposes set forth.

11. In sand-molding apparatus, the combination of a jarring-table, a flask, a sand-feeding chute supported on the table a short distance above the top of the flask, and a cutting-frame carrying a wire, said frame being adapted to pass within the space between the flask and chute, substantially as and for the purposes set forth.

12. In sand-molding apparatus, the combination of a jarring-table, a flask, a sand-feeding chute supported on the table a short distance above the top of the flask, and a cutting-frame carrying a wire and back of the same a sleeker, and adapted to pass in the space between the flask and chute substantially as set forth.

13. In sand-molding apparatus, the combination of a jarring-table, a flask and a sand-feeding chute supported on the table independently of the flask and having wires extending across near the base thereof to support the sand therein, substantially as set forth.

14. In sand-molding apparatus, the combination of a jarring-table, a flask, a sand-feeding chute supported on and movable with the jarring-table, a permanent sand-reservoir above and at one side of the chute and a horizontally-moving transfer-box adapted to receive the sand from the reservoir and pass over and deliver it to the chute, substantially as set forth.

In testimony whereof I, the said STEPHEN JARVIS ADAMS, have hereunto set my hand.

STEPHEN JARVIS ADAMS.
